UNITED STATES PATENT OFFICE

WILSON L. BLAYNEY, OF CHICAGO, ILLINOIS, ASSIGNOR TO MARSHALL FIELD & COMPANY, OF CHICAGO, ILLINOIS, A CORPORATION OF ILLINOIS

SCARF AND METHOD OF MAKING THE SAME

Application filed September 3, 1931. Serial No. 580,981.

This invention relates to scarfs and the making thereof, and it is an important object of the invention to avoid the necessity of a merchant carrying a large number of 5 separate scarfs in loose condition such that they must of necessity be handled and rehandled many times in the retail sale thereof both by purchasers and sales persons to the impairment and damage of the scarfs.

10 In carrying out the invention, I take a continuous piece of scarf material, having the usual selvage edges, and I provide thereon a longitudinal series of scarf designs disposed and arranged in accordance with the present 15 invention so that individual scarfs may be cut from the free end portion of the strip of material as the scarfs are needed for immediate sale without disturbing the other scarf areas which remain in the piece of material in an undistributed condition, thus preserving the remaining scarf areas in an unhandled and consequently clean and satisfactory condition.

Thus my invention enables the selling of 25 scarfs from the various stores in the form of piece goods alongside of goods of the same pattern, material, and quality, so that a scarf can be provided of the same material, pattern and like as a dress, thus serving to enhance 30 the ensemble effect so much desired in the modern trend of dressing.

These and other objects of my invention will be more fully understood by reference to the accompanying sheet of drawing, in 35 which—

Figure 1 is a diagrammatic end view of the apparatus for carrying out my invention;

Figure 2 is an elevational view of a piece of 40 material having the unit areas imprinted thereon; and

Figure 3 is an elevational view of a completed scarf.

Referring now specifically to the drawing, and in which like reference characters refer 45 to like parts throughout, a piece of material 10 having opposite longitudinal selvage edges is passed between a lower roll 11 and an upper roll 12 over supporting members 13 and 14 at each side of the rolls 11 and 12. The roll 50 12 has a duct roll 15 mounted adjacent there-

to and in peripheral contact therewith, the roll 15 in turn contacting with a fountain roll 16 mounted upon a fountain 17, containing the necessary dye for use in printing the unit areas upon the piece of goods. 65

The upper roll 12 has areas thereon prepared in the usual manner of print rolls for use in printing piece goods and containing the proper configurations for the pattern which it is desired to impress upon the material and arranged so that when the material 10 is placed between the rolls the unit areas extend diagonally thereacross. 70

It will be understood that various kinds of 75 designs can be placed on these rolls. In Figure 2 a plurality of scarfs 18 is shown, in which a body portion 19 is shown having a border 20 therearound which is separated by a line 21 extending between the body portion 19 and the border 20. 70

The print roll 12 is approximately 16 inches in circumference. The strip of material 10 is forty inches wide, with the print area on the roll 12 extending spirally therearound at an angle of approximately 45° so that when 75 the material is printed the scarf or unit areas conforming to the scarf, extend across the material at an angle of approximately 45° and thereby produce a scarf approximately 57 inches long. The dimensions, of course, 80 can be varied in any manner desired, depending upon the kind of scarfs it may be desired to produce.

After the material is printed, as shown in 85 Figure 2, it is cut, along the bias areas between successive unit areas into strips, see Fig. 3 as for instance along the lines 22, 22 shown on the drawing but which may or may not appear on the goods. When the material is cut into strips, the cut will be 90 along the line of the bias of the goods, as known in the dress making art, and therefore the scarf will have opposite longitudinal cut bias edges and opposite uncut transverse selvage end edges. It will be thus understood 95 that by printing the goods in the fashion above described, the piece goods can be prepared in the usual manner and sold from the counters, it only being necessary for the sales person to cut a scarf along the line 22 100

in order to provide a completed scarf, and that similar goods conforming in pattern to the body of the scarf or to the border thereof, can be provided so that a complete ensemble effect is maintained in having a scarf and dress of the same pattern and design.

From the foregoing description, it will be understood that the method of the present invention produces a new article of manufacture from which bias unit scarf areas, preferably in the form of parallelograms, may be cut for sales purposes, such article comprising a continuous piece of scarf material having longitudinal selvage edges and upon which material there is provided a longitudinal series of parallel ornamented unit areas with each unit area extending diagonally across the piece of material substantially on the bias thereof and including a border defining the outline of the ornamented area, the longitudinal dimension of each unit area extending across the piece of material and of greater length than the transverse width of the unit area, the adjacent longitudinal border portions of successive unit areas extending from edge to edge of the material and being in mutual close relation and defining therebetween a bias severing area extending entirely across the material and along which the material may be cut to obtain a separate bias unit area having opposite uncut transverse end selvage edges and opposite longitudinal cut bias edges.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. As a new article of manufacture, scarf goods from which bias unit scarf areas in the form of parallelograms may be cut for retail sale purposes, a continuous piece of scarf material provided with longitudinal selvage edges and having printed upon the material a longitudinal series of parallel ornamented unit parallelogram areas, each unit area extending diagonally across the piece of material substantially on the bias thereof and including a printed border defining the outline of the ornamented area, the longitudinal dimension of each unit area extending crosswise of the piece of material and of greater length than the transverse width of the unit area; the adjacent longitudinal border portions of successive unit areas extending from edge to edge of the material and being in mutual close relation and defining therebetween a bias severing area extending entirely across the material and along which the material may be cut to obtain a separate bias unit area having opposite un-

cut transverse selvage end edges and opposite longitudinal cut bias edges.

2. The herein described method of making scarfs, which comprises printing, upon a continuous piece of scarf material provided with longitudinal selvage edges, a longitudinal series of parallel ornamented unit parallelogram areas with each unit area extending diagonally across the piece of material substantially on the bias thereof, and also printing borders enclosing and defining the outline of the respective unit areas and extending from edge to edge of the material, with the adjacent longitudinal border portions of successive unit areas in mutual close relation, and severing the piece of material along the bias severing area located between successive borders to separate the piece of material along the bias thereof into a plurality of bias unit scarfs having opposite uncut transverse end selvage edges and opposite longitudinal cut bias edges.

3. The herein described method of making scarf goods, which comprises producing, upon a continuous piece of scarf material provided with longitudinal selvage edges, a longitudinal series of parallel ornamented unit areas including borders therefor with each unit extending substantially on the bias of the material and from edge to edge thereof, with the adjacent longitudinal border portions of successive unit areas in mutual close relation.

4. The herein described method of making scarf goods, which comprises printing, upon a continuous piece of scarf material provided with longitudinal selvage edges, a longitudinal series of parallel ornamented unit areas including borders therefor with each unit extending substantially on the bias of the material and from edge to edge thereof, with the adjacent longitudinal border portions of successive unit areas in mutual close relation.

5. The herein described method of making scarf goods, which comprises roller printing, upon a continuous piece of scarf material provided with longitudinal selvage edges, a longitudinal series of parallel ornamented unit areas including borders therefor with each unit extending substantially on the bias of the material and from edge to edge thereof, with the adjacent longitudinal border portions of successive unit areas in mutual close relation.

6. The herein described method of making scarfs which comprises producing, upon a continuous piece of scarf material provided with longitudinal selvage edges, a longitudinal series of parallel ornamented unit areas including borders therefor with each unit extending substantially on the bias of the material and from edge to edge thereof, with the adjacent longitudinal border portions of successive unit areas in mutual close rela-

tion, and severing the piece of material along the bias severing area located between successive borders.

7. As a new article of manufacture, scarf goods from which bias unit scarf areas may be cut for sale purposes, a continuous piece of scarf material provided with longitudinal selvage edges and having upon the material a longitudinal series of parallel ornamented unit areas including borders therefor, each unit extending substantially on the bias of the material and from edge to edge thereof with the adjacent longitudinal border portions of successive unit areas in mutual close relation.

8. As a new article of manufacture, scarf goods from which bias unit scarf areas may be cut for sale purposes, a continuous piece of scarf material provided with longitudinal selvage edges and having printed upon the material a longitudinal series of parallel ornamented unit areas including borders therefor, each unit extending substantially on the bias of the material and from edge to edge thereof with the adjacent longitudinal border portions of successive unit areas in mutual close relation.

9. As a new article of manufacture, scarf goods from which bias unit scarf areas may be cut for sale purposes, a continuous piece of scarf material provided with longitudinal selvage edges and having printed upon the material a longitudinal series of parallel ornamented unit areas each unit area extending diagonally of the piece of material substantially on the bias thereof and including a printed border defining the outline of the ornamented area, the adjacent longitudinal border portions of successive unit areas extending from edge to edge of the material and lying in mutual close relation and defining therebetween a bias severing area extending entirely across the material and along which the material may be cut to obtain a separate bias unit area having opposite uncut transverse selvage end edges and opposite longitudinal cut bias edges.

Signed at Chicago, Illinois, this 24th day of August, 1931.

50 WILSON L. BLAYNEY.
